UNITED STATES PATENT OFFICE.

EDWARD MELDAL, OF LONDON, ENGLAND.

APPARATUS FOR USE IN THE REPAIR OF ROADS AND THE LIKE.

1,424,507.

Specification of Letters Patent. Patented Aug. 1, 1922.

Application filed October 5, 1920. Serial No. 414,797.

To all whom it may concern:

Be it known that I, EDWARD MELDAL, of London, England, gentleman, have invented certain new and useful Improvements in 5 Apparatus for use in the Repair of Roads and the Like, of which the following is a specification.

This invention relates to a vehicular apparatus for use in the repair of roads and the 10 like and the object is to provide a simple and efficient apparatus for the purpose stated which will have the property of great mobility and will render the hitherto laborious operations of repair much more rapid 15 and easy than hitherto.

The invention consists in the novel features, combinations and arrangements of parts, all as hereinafter fully described and specifically pointed out in appended claims 20 with reference to the accompanying drawings, in which Fig. 1 is a side elevation and Fig. 2 a plan view of one embodiment of the invention given as an example.

The apparatus shown comprises a strong 25 vehicular frame *a* mounted on running wheels *a*¹ say four in number, any or all of which may be driven for propulsion of the vehicle as by means of an internal combustion engine located within the bonnet *a*² or 30 other source of power carried by the frame, say at the front thereof, with the usual or any approved system of transmission between the engine and wheels and with any desired form of steering *a*³ and control 35 mechanism.

Mounted in the frame *a* suitably between the front and rear wheels is a heavy roller *b*⁴ for rolling the surface of the road after repairing or patching materials have been 40 laid, this roller being, for example, hollowed to a considerable extent and adapted for the ready removal and insertion of weights which may be in the form of detachable segments so that the effective weight of the 45 roller may be varied according to the requirements of the work to be performed or other existing conditions, or the roller may be capable of holding water as ballast. This roller is so mounted in the frame that it can 50 be raised and lowered at will, that is to say, when out of active use the roller will be raised and permit the vehicle to travel under the action of the propelling means at any speed within the capacity of the motive 55 power, and when in use to be lowered on to the road surface for rolling same. The rais-

ing and lowering mechanism may be actuatable from the engine or propelling means, but the means shown is manual and consists in providing the roller with bearings *b*¹, 60 one at each side, and each slidably in a slot *b*² in a bar *b*³ which is under the action of an eccentric *b*⁴ on a shaft *b*⁵ provided with a worm wheel *b*⁶ with which engages a worm *b*⁷ on a vertical shaft *b*⁸ which latter is rotated 65 through worm gear *b*⁹ from a hand crank *b*¹⁰ supported by a pillar *b*¹¹ carried on an upper platform *h* hereinafter referred to. Very considerable reduction of gearing is thus obtained which will permit the roller 70 to be raised and lowered by hand. When actuating the roller from the engine, worm-gear may be used and suitable shafting driven, for instance through forward and reverse transmission mechanism with necessary clutch devices, or through pairs of bevel-gears with means for shifting same for forward or reverse drive so that the roller may be raised or lowered according to requirements. The control by the engine 80 could also be adapted to operate the eccentric mechanism described for manual operation. The roller may be divided into a number of sections or separate elements *b*¹² as shown in Fig. 2. 85

I also provide in addition to the main roller *b* other lateral rollers *c*, *c*¹, for instance, one at each side of the apparatus, for dealing with repairing or finishing material which has been laid adjacent the edges, gutters or kerbs of the roadway and which cannot be reached by said main roller *b*. These lateral rollers are shown as mounted in forks *c*² capable of being raised and lowered as by means of worm gear *c*³ on transverse 95 shaft *c*⁴ driven by a vertical shaft *c*⁵ rotated by hand wheel *c*⁶ carried by the platform *h* above referred to. Other forms of transmission may be used, for instance, similar to that for the main roller *b* and where 100 necessary, provision is also made for anchoring said rollers in their raised position, as by means of a chain or wire rope *d* passed over or connected to suitable members *d*¹ extending from the frame *a*. 105

In addition to the roller or rollers above described I contemplate providing the apparatus with one or more suitably disposed tampers or rammers *e* by which the repairing material may be stamped or rammed into 110 place, such devices being of particular value in repairing what are known as "pot-holes."

2
These tampers may with advantage be placed near the rear of the vehicle under ready control of the operator and be operated by lift cams or tappets arranged to 5 raise them to a desired height and then suddenly release them so that they perform their function by gravity, or in lieu of this, some means of positively actuating the tampers may be provided, such as by an eccentric 10 motion.

In the drawings a single tamper is shown, capable of being traversed both longitudinally and transversely of the apparatus within limits determined by the frame structure thereof so that a considerable range of 15 movement may be provided for. This traversing movement may be effected by slidably mounting the tamper support e^1 on rods and providing separate means for adjusting 20 it thereon in both directions, these adjusting means being shown as comprising screwed rods e^2 for longitudinal adjustment operated by bevel-wheels e^3 from cross shaft e^4 , which in turn is rotated by bevel-wheels e^5 from 25 vertical shaft e^6 and hand-wheel e^7 the latter mounted on the platform h .

For transverse adjustment the tamper support carries a transverse shaft f , driven through bevel-gears f^1 from vertical shaft f^2 30 which in turn is actuated through other bevel-gears f^3 , carried by a bracket f^4 slideable on a keyed shaft f^5 driven by chain gear f^6 from a hand wheel f^7 carried by the platform h . The construction is such that the 35 adjusting means do not interfere with the means used for raising and lowering the tamper. These latter means are shown as including snail cams g adapted to engage under projections g^1 on the tamper stem g^2 40 and permit the tamper to drop by gravity when the summits of the cams are passed. The cams are mounted on a shaft g^3 to which rotation is imparted through chain-gear g^4 and bevel-gearing g^5 from shaft g^6 driven 45 from the engine or other source of power. The shaft g^6 is keyed so that the bevels may slide thereon to permit of adjustment of the tamper. Cams of different sizes may be used 50 to provide a varying drop for the tamper and the tamper can be weighted if desired. The tamper may be replaced by a scarifying device, if desired, operated in a similar manner, or prongs or points can be attached to the base of the tamper.

55 A still further feature of the invention consists in the provision of a raised platform h preferably at the front of the vehicle from which the operator can control the engine and steering handle a^8 and on which 60 as aforesaid are also mounted controlling or actuating devices b^{10} , e^1 , c^6 and f^7 for the rollers and tamper, and also for other elements to be described later. The platform and the said devices are so located and arranged that the operator has a clear view of

the operation of all said elements and can thus properly manipulate same.

Beneath said platform receptacles may be provided, one h^1 , for example for water for distribution by pipe h^2 to the road surface adjacent the roller b , and the other h^3 for road repairing or finishing materials with means such as pipe h^4 for conveying said materials into the path or paths of the rollers b and c c^1 , and a further receptacle or 75 receptacles i may also be provided at the rear of the vehicle divided into compartments for containing water and road repairing or finishing material which may be led by convenient means such as chutes i^1 to 80 positions for treatment by the tamper e , the discharge of said water and material from said receptacles being preferably under the control of the operator from the raised platform h aforesaid by any convenient means 85 as will be readily understood. One or more tanks j can also be located above the platform in such position as not to obscure the view of the tamping and general control 90 above referred to.

90 What I claim as my invention and desire to secure by Letters Patent of the United States is:—

1. An apparatus for use in road repairs comprising in combination a vehicular frame 95 carrying a main heavy roller, means for raising and lowering said roller from and to the ground, and means by which part of the weight of the vehicle may be thrown onto the roller when in action whilst retaining 100 pressure on the running wheels of the vehicular frame sufficient for their proper function.

2. An apparatus for use in road repairs comprising a self propelled vehicular frame 105 and a tamper or tampers with means for adjustment thereof longitudinally and transversely of the apparatus for stamping patching or repairing material.

3. An apparatus for use in road repairs 110 comprising a self-propelled vehicular frame and a tamper or tampers with means for adjustment thereof longitudinally and transversely of the apparatus for stamping patching or repairing material, said tamping device being operable from the propelling means of the vehicle and means for manual adjustment of the tamper.

4. An apparatus for use in road repairs 115 comprising a self-propelled vehicular frame and a tamper or tampers with means for adjustment thereof longitudinally and transversely of the apparatus for stamping patching or repairing material, said tamping device being operable from the propelling 120 means of the vehicle and means for manual adjustment of the tamper, adjusting means being adapted to permit proper operation of the tamper in what ever position it may be 125 caused to assume.

5. Apparatus for use in repairing roads and the like comprising in combination a vehicular frame, carrying a main heavy roller, means for raising and lowering said roller from and to the ground and tamping means with devices for adjustment thereof longitudinally and transversely of the apparatus for stamping patching or repairing material. 45
6. Apparatus for use in repairing roads and the like comprising in combination a vehicular frame, carrying a main heavy roller, means for raising and lowering said roller from and to the ground, one or more additional lateral rollers for treating repair material not reachable by the main roller, means for raising and lowering said additional roller or rollers from and to the ground, and tamping means with devices for adjustment thereof longitudinally and transversely of the apparatus for stamping patching or repairing material. 50
7. Apparatus for use in repairing roads and the like comprising in combination a vehicular frame, carrying a main heavy roller, means for raising and lowering said roller from and to the ground, one or more additional lateral rollers for treating repair material not reachable by the main roller, means for raising and lowering said additional roller or rollers from and to the ground, tamping means with devices for adjustment thereof longitudinally and transversely of the apparatus for stamping patching or repairing material, a raised platform from which the control and steering of the vehicle may be performed, and devices carried by said platform, for controlling the operation of the rollers and the adjustment and operation of the tamping means, said operations and adjustment being visible from the platform. 55
8. An apparatus for use in road repairs comprising in combination a vehicular frame carrying a main heavy roller, means for raising and lowering said roller from and to the ground, one or more additional lateral rollers for treating repair material not reachable by the main roller, means for raising and lowering said additional roller or rollers from and to the ground, receptacles carried by the vehicle for containing water and road material and means for discharging same adjacent the rollers. 60
9. Apparatus for use in repairing roads and the like comprising in combination a vehicular frame, carrying a main heavy roller, means for raising and lowering said roller from and to the ground, one or more additional lateral rollers for treating repair material not reachable by the main roller, means for raising and lowering said additional roller or rollers from and to the ground tamping means with devices for adjustment thereof longitudinally and transversely of the apparatus for stamping patching or repairing material, a raised platform from which the control and steering of the vehicle may be performed, and devices carried by said platform, for controlling the operation of the rollers and the adjustment and operation of the tamping means, said operations and adjustment being visible from the platform, receptacles below the platform and at the rear of the vehicle for containing water and road material and means for discharging the contents of said receptacles at points adjacent the rollers and tamping means. 65
- In witness whereof I have signed this specification in the presence of two witnesses: 70
- EDWARD MELDAL.
